Supplementary European Search Report issued in PCT/US2007/006594, Mar. 10, 2010.

Primary Examiner — Susan E Krakower(74) *Attorney, Agent, or Firm* — Workman Nydegger(57) **CLAIM**

The ornamental design for a pair of struts for an orthopedic device, as shown and described.

DESCRIPTION

FIG. 1 is a perspective view of a pair of struts for an orthopedic device showing the design.

FIG. 2 is a front elevational view showing the strut of FIG. 1.

FIG. 3 is a top plan view showing the strut of FIG. 1; and, FIG. 4 is a bottom plan view showing the strut of FIG. 1.

The broken lines are included for the purpose of illustrating environmental structure and form no part of the claimed design.
